UNITED STATES PATENT OFFICE.

GEORGE W. NELSON, OF CLEVELAND, OHIO, ASSIGNOR TO THE STANDARD SEWING MACHINE COMPANY, OF CLEVELAND, OHIO, A CORPORATION OF OHIO.

STOP MECHANISM FOR SEWING-MACHINES.

1,282,107.

Specification of Letters Patent.

Patented Oct. 22, 1918.

Original application filed March 2, 1912, Serial No. 681,208. Divided and this application filed July 10, 1917. Serial No. 179,658.

To all whom it may concern:

Be it known that I, GEORGE W. NELSON, a citizen of the United States, and resident of Cleveland, in the county of Cuyahoga and State of Ohio, have invented certain new and useful Improvements in Stop Mechanism for Sewing-Machines, of which the following is a specification.

This invention relates to stop mechanism for sewing machines and more particularly to stop mechanism for that class of sewing machines in which successive groups or series of stitches are made at separated points in the work, as for example, in button-sewing machines, such as disclosed in my pending application Serial No. 681,208, of which this present application is a division.

The main object of the invention is to provide an improved mechanism for automatically stopping the machine on the completion of a predetermined series of group of stitches and to effect such stopping quickly and without undue jar or strain on the machine parts.

The stop mechanism employed in the attainment of this object embodies suitable braking devices for engaging opposite sides or faces of a suitable rotary driven member, such as the fast pulley generally employed in these machines, and in connection with these braking devices means are preferably provided for bringing the brake quickly into action when a spring or other suitable power device controlling the brake is released at the proper point in the operation of the machine, to wit, on the completion of the predetermined series or group of stitches.

Referring now to the accompanying drawings forming part of this specification,—

Figure 1 is a rear side elevation of a button-sewing machine provided with my improved stop mechanism, with the parts shown in the position they occupy upon the stopping of the machine;

Fig. 2 is a similar view, with the front end of the machine broken away and showing the stop mechanism in the position it occupies during the operation of the machine and just prior to being tripped; and

Fig. 3 is a detail illustrating the construction and operation of one of the braking devices of the stop mechanism, the view being taken from the front side of the machine or the side opposite that shown in Figs. 1 and 2.

Similar reference characters indicate like parts in the several figures of the drawings.

As the stop mechanism embodying my invention is applicable to various specific types of sewing machines, it will not be necessary to here give any detailed description of the sewing machine shown, as any desired description of this may be had by reference to my aforesaid pending application.

The machine, as shown, embodies a main frame comprising upper and lower portions, 2 and 3, suitably connected and adapted for the support of the various parts of the operating mechanism. The main driven member of the machine is illustrated as a fast pulley, 4, associated with a loose or driving pulley, 5, these two pulleys being, as is usual, in the form of hand wheels to permit of their being readily manipulated by the operator. The fast pulley 4 is shown as secured to a main driven shaft 6, which extends substantially from end to end of the lower section 3 of the frame and from which the several operating parts of the machine are driven through suitable connections in usual manner. Associated with the fast and loose pulleys 4 and 5 is my improved stopping and starting mechanism which will now be described:

One of the principal features of the improved starting and stopping mechanism embodied in the machine shown is the provision of means for engaging the principal driven member or fast pulley 4 at opposite sides thereof when the machine is to be automatically stopped. Two braking surfaces are provided for this purpose, which surfaces should of course be clear of said driven member when the machine is in operation. The two braking devices may be of any suitable construction and may be operated in any desired way so long as they are constructed and operated in such a manner as to clamp said driven member between them when the machine is to be stopped. The stopping means will, however, preferably include a suitable quick-acting device, such as a strong spring, for applying these braking devices substantially instantaneously to opposite sides of said driven member when the machine is to be stopped. In the construction shown the fast and loose pulleys are forced into engagement with each other by a suitable starting lever, such as 36, having

in line with the center of the pulley 5 a cone-pointed pin 37, holding the two pulleys firmly together during the time that the operator desires the machine to be running.

5 Associated with the pulleys 4 and 5 is shown another lever, such as 38, of substantially ring form surrounding said pulleys. In this case the two levers 36 and 38 are substantially parallel to each other and suitably 10 pivoted at corresponding ends to the lower half frame of the machine. At its upper end the starting lever 36 is shown as having a forwardly and downwardly extending or overhanging arm, 39, the inner face of 15 the depending portion of which carries a suitable frictional or braking device, 40, in juxtaposition with the forward side of the pulley 4. The ring-shaped lever 38 is also shown as having near the upper side thereof 20 of a corresponding frictional or braking device, 41, substantially in horizontal alinement with that shown at 40. These two levers 36 and 38 and the braking devices or pads carried thereby are intended to be 25 moved simultaneously in opposite directions, the main portions of said levers, that is, the levers proper, moving away from each other to apply the brake, and moving toward each other when the brake is removed and the pulleys coupled together. Any suitable means 30 may be employed for operating said levers in this manner provided that said means is such as to effect a quick and powerful application of the brake. In order to accomplish this a toggle connection is preferably combined with a strong spring, 44', the latter serving to effect a quick application of the braking devices 40 and 41 to the pulley 4, while the toggle serves to obtain a powerful grip through said braking device upon 35 the opposite sides of said pulley 4. A toggle connection suitable for this purpose is indicated herein, comprising in this case a pair of links, 42 and 43, connected respectively to the starting lever 36 and to a fixed point on the upper frame 2 of the machine, the links of the toggle at their point of connection being also pivoted to a third link, 44, the upper end of which is in turn pivoted to a rock-arm 45' of a rock shaft, 45, 40 journaled in bearings in lugs projecting from the upper rear end of said main frame 2, said rock shaft also having secured thereto at its front end two rock arms, 46, and 47, and at its rear end a rocking pawl 48. The rock arm 46 is intended to be operated by connections from a treadle or other suitable part to start the machine, while the rocking pawl 48 constitutes one element of 45 a holding device or detent, and is adapted to be engaged by a complementary holding element or detent, which in the present case is the hooked upper end, 49, of a long lever, 50, pivoted near the center on a suitable 55 fixed portion of the frame of the machine,

and having its lower end suitably faced or beveled, as indicated at 51, for coöperation with tripping means which will be herein-after described.

The rock arm 47 is shown as connected by 70 means of a rod, 52, to the free end of a rock arm, 53, secured to one end of a rock shaft, 54, journaled in bearings at the rear end of the machine and having a pair of eccentrics, 55, formed thereon for coöperation with the 75 forward ends of a pair of substantially horizontal links, 56, the rear ends of which are connected to the ring-shaped lever 38 near the upper end thereof. The construction of these parts and the mode of organization 80 thereof is such that when the starting lever is moved rearwardly or in a direction to release the driving pulley from the driven pulley the toggle is straightened, and at the same time, through the connections from the 85 rock shaft 45 to the rock shaft 54, the links 56 are moved forward slightly by the eccentrics 55, their movement being small as compared with the rearward movement of the starting lever, and the two braking devices 40 and 41 are brought instantaneously and with powerful combined spring and toggle action, into braking engagement with 90 opposite sides of the pulley 4 to stop the machine. In connection with these braking devices means will preferably be employed for assuring the stopping of the machine each time with all of the parts in a predetermined position, to wit, with the take-up 13 in raised 95 position to take the first stitch of the next 100 succeeding series. The means here used for this purpose is a wedge for increasing the friction opposed to the rotation of the parts at a predetermined point. Such a wedge or cam is shown at 4' on the pulley 4 and operates with the braking device 40 on the starting lever 36 and the braking device 41 on the ring-lever 38 to wedge said pulley between said braking surfaces and bring the 105 machine quickly, but with a properly graduated action, to a stop at the exact point desired. To start the machine the operator presses down a treadle or other suitable device and through suitable connections, one of which is shown at 57, to the rock arm 46, 110 the rocking pawl 48 is drawn down until it passes below the hook 49 of the detent lever 50 when it is engaged by said hook or detent, as shown in Fig. 2, which is normally forced toward said rocking pawl, as by means of a 115 spring 58. This movement of the connecting rod 57 serves to release the toggle and withdraw the braking devices from the opposite faces of the pulley 4, and in these positions the parts are held by the detent just described until the lever 50 is tripped automatically on the completion of a predetermined series or group of stitches.

Any suitable means may be employed for effecting the tripping of the devices just 120

described. Preferably, however, suitable releasing or tripping means operated from the main shaft 6 through a cross shaft, such as 59, will be employed. Here this cross shaft 5 is journaled in suitable bearings in the lower frame member 3 of the framing, and is driven from the main shaft by suitable worm gearing, (not shown) by means of which a relatively slow rotary movement is im- 10 parted to said cross shaft 59. On the completion of the making of a predetermined number of stitches a suitable releasing device may be brought into operation by said cross shaft. In the construction shown said 15 cross shaft carries at its rear end a relatively thick disk 62, in which one or more radially movable pins, such as 63, may be supported for sliding movement. These pins may be held either in or out of opera- 20 tive position as by suitable clamping devices, such as 64. Where a single pin projects, as shown in the drawings, the automatic stop mechanism will be tripped once on each complete rotation of the cross shaft 25 59; whereas if both of the pins shown so project said stop mechanism will be tripped twice on such rotation of the cross shaft. Both of these pins may be drawn in and securely clamped out of action when it is de- 30 sired to use the machine for straight-away stitching without automatic stoppage of the mechanism periodically. On the completion of the predetermined rotary movement of the shaft 59 and the disk 62, that is, on the 35 completion of the making of the predetermined series or group of stitches, the pin 63 will come in contact with one of the faces 51 of the detent lever 50 and release the lever from the rocking pawl 48, whereupon the 40 automatic stopping of the mechanism will ensue, as previously described. The tripping means illustrated is shown as normally covered by a swinging plate, such as 65.

What I claim is:—

- 45 1. In a sewing machine and in combination, rotary driving and driven members, a starting lever therefor, stitch-forming mechanism, and an automatic stop mechanism comprising a pair of braking surfaces at op- 50 posite sides of said driven member and nor- mally out of engagement therewith and one of which is carried by said starting lever, and means for bringing said surfaces into engagement with opposite sides of said driven 55 member.
2. In a sewing machine and in combination, rotary driving and driven members, a starting lever therefor, a second lever, stitch-forming mechanism, and an auto- 60 matic stop mechanism comprising a pair of braking devices at opposite sides of said driven member and normally out of engagement therewith and carried respectively by said levers, and means for simultaneously 65 moving said levers in opposite directions to

bring said braking surfaces into engagement with opposite sides of said driven member.

3. In a sewing machine and in combination, rotary driving and driven members, 70 stitch-forming mechanism, and an automatic stop mechanism comprising a pair of braking devices at opposite sides of said driven member and normally out of engagement therewith, means including a spring tending 75 to bring said braking surfaces into engagement with opposite sides of said driven member, and a detent normally restraining said spring.

4. In a sewing machine and in combina- 80 tion, rotary driving and driven members, stitch-forming mechanism, and an automatic stop mechanism comprising a pair of braking devices at opposite sides of said driven member and normally out of engagement 85 therewith, means including a spring tending to bring said braking surfaces into engagement with opposite sides of said driven member, a detent normally restraining said spring, and means for tripping said detent. 90

5. In a sewing machine and in combina- 95 tion, rotary driving and driven members, stitch-forming mechanism, and an automatic stop-mechanism comprising a pair of braking devices at opposite sides of said driven member and normally out of engagement therewith, means including a toggle connec- 100 tion and a spring for bringing said surfaces into engagement with opposite sides of said driven member, a detent normally restraining said spring, and means associated with the stitch forming mechanism for automatically tripping said detent on the completion of a predetermined group of stitches.

6. In a sewing machine and in combina- 105 tion, rotary driving and driven-members, a main shaft driven thereby, stitch-forming mechanism, and an automatic stop mecha- 110 nism comprising a pair of braking surfaces at opposite sides of said driven member and normally out of engagement therewith, means normally under restraint for bringing said surfaces into engagement with opposite sides of said driven member, and releasing means controlled by the main 115 shaft for permitting the operation of said last mentioned means.

7. In a sewing machine and in combina- 120 tion, rotary driving and driven members, a main shaft driven thereby, stitch-forming mechanism, and an automatic stop mecha- 125 nism comprising a pair of braking surfaces at opposite sides of said driven member and normally out of engagement therewith, means normally under restraint for bringing said surfaces into engagement with opposite sides of said driven member, a cross shaft operated by the main shaft, and a trip actuated by said cross shaft for re- 130 leasing said last mentioned means.

8. In a sewing machine and in combination, rotary driving and driven members, a starting lever therefor, a pivoted ring adjacent to said driven member, stitch-forming mechanism, and an automatic stop mechanism comprising a pair of braking surfaces at opposite sides of said driven member and normally out of engagement therewith and carried respectively by said starting lever and said ring, and means for simultaneously moving said starting lever and said ring in opposite directions to bring said braking surfaces into engagement with opposite sides of said driven member.
9. In a sewing machine and in combination, rotary driving and driven members, stitch-forming mechanism, and an automatic stop mechanism comprising a pair of braking devices at opposite sides of said driven member and normally out of engagement therewith, and means including a toggle connection and a spring for normally straightening said toggle for bringing said surfaces into engagement with opposite sides of said driven member, said driven member being provided with a cam surface for coöperating with the braking devices to bring the machine to a gradual stop with its parts in predetermined positions.
10. In a sewing machine and in combination, rotary driving and driven members, stitch-forming mechanism, and an automatic stop mechanism comprising a pair of braking devices at opposite sides of said driven member and normally out of engagement therewith, and means for bringing said surfaces into engagement with opposite sides of said driven member, said driven member being provided with a cam surface for coöperating with the braking devices to bring the machine to a stop with its parts in predetermined positions.

matic stop mechanism comprising a pair of braking devices at opposite sides of said driven member and normally out of engagement therewith, and means for bringing said surfaces into engagement with opposite sides of said driven member, said driven member being provided with a cam surface for coöperating with the braking devices to bring the machine to a stop with its parts in predetermined positions.

11. In a sewing machine and in combination, rotary driving and driven-members, stitch-forming mechanism, and an automatic stop mechanism comprising a pair of braking devices at opposite sides of said driven member and normally out of engagement therewith, and means for bringing said surfaces into engagement with opposite sides of said driven member, said driven member being provided with means for coöperating with the braking devices to increase the friction opposed to the rotation of the member at a predetermined point, for the purpose set forth.

Signed at Cleveland, in the county of Cuyahoga and State of Ohio, this 2nd day of July, A. D. 1917.

GEORGE W. NELSON.
